W. BRÄGGER

SPARK PLUG FOR COMBUSTION ENGINES

Filed March 12, 1921

FIG.1.

FIG. 3.

FIG. 4.

FIG. 2.

FIG. 5.

Inventor:
Walter Brägger
by Otto K. Gringenbauer
his attorney.

UNITED STATES PATENT OFFICE.

WALTER BRAGGER, OF BERLIN, GERMANY.

SPARK PLUG FOR COMBUSTION ENGINES.

Application filed March 12, 1921. Serial No. 451,742.

(GRANTED UNDER THE PROVISIONS OF THE ACT OF MARCH 3, 1921, 41 STAT. L., 1313.)

To all whom it may concern:

Be it known that I, WALTER BRÄGGER, a citizen of Switzerland, residing at Berlin, in the Free State of Prussia, Germany, have 5 invented Improvements in Spark Plugs for Combustion Engines (for which I have filed application in Germany, November 6, 1918, and obtained Patent No. 321856, on February 27, 1920); and I do hereby declare 10 the following to be a full, clear, and exact description of the same.

My invention relates to improvements in spark plug for combustion engines, and one of the objects of the improvements is 15 to provide a spark plug in which the terminals are protected as against excessive heating. Another object of the improvements is to provide a spark plug in which the terminals are automatically cleaned 20 from undesirable deposits such as oil and soot. With these and other objects in view my invention consists in providing a metallic body such as a ball near the terminals which is adapted to be moved by the 25 compression within the cylinder of the combustion engine into position spaced from and intermediate the terminals. In the preferred form of the invention the ball is confined within a chamber which opens into 30 the cylinder and has its opening normally closed by said metallic body.

Another object of the improvements is to provide a spark plug having an elongated terminal provided with a longitudinal passage connecting said chamber with the outer air.

My invention also relates to the manner of mounting the ball and the terminals within the plug, to the construction of the 40 insulating means and the means for arresting the metallic body in its positions, all of which will be described hereinafter reference being had to the accompanying drawing and to the reference characters marked 45 thereon.

For the purpose of explaining the invention several examples embodying the same have been shown in the accompanying drawing, in which the same reference characters 50 have been used in all the figures to indicate corresponding parts.

In said drawing,—

Fig. 1, is a longitudinal section of the plug,

Fig. 2, is a cross-section taken on the 55 line A—B of Fig. 1,

Fig. 3, is a longitudinal section showing a modification,

Fig. 4, is a longitudinal section showing a further modification, and 60

Fig. 5, is a plan view of Fig. 4.

In the example shown in Figs. 1 and 2, my improved spark plug comprises a tubular body 1 made of a material which is a conductor for electricity such for example as iron, steel, brass, bronze, or the like, and adapted to be screwed into the wall of the cylinder of a combustion engine. The lower part 2 of the body 1 beginning from a shoulder 4 is provided with a male 70 thread 3 and it is provided at its lower terminal with a spherical flange 5 providing a hole or seat 6 for a ball 7 confined within the chamber provided by the part 2. The diameter of the ball is larger than that of 75 the seat 6, so that the ball can not drop therethrough. The upper part 10 of the body 1 is of greater inner diameter than the lower part, and between the said parts there is a shoulder 8 providing a support 80 for a washer 8¹. The upper part of the body 1 is formed with an increased outer diameter and it is provided with a female thread 9.

Within the body 1 there is a coaxial sleeve 85 11 of insulating material such as porcelain, which is formed with an enlarged outer portion 12 the lower shoulder 13 of which engages the washer 8¹. The upper shoulder 14 provided by the enlarged portion is engaged by a screw-threaded gland 30 by means of which the body 11 is kept in position within the body 1.

The lower end 15 of the sleeve 11 is provided, and its bore is such that the ball 95 7 can only partially get into the same, as is shown in Fig. 1 in dotted lines. The upper part of the sleeve 11 is made internally with an increased diameter and between the upper and lower parts there is a shoulder 16 100 providing an abutment for a cylindric insulator 17 of porcelain.

The insulator 17 provides a guide for the stem 20 of the sparking terminal which is formed at its lower conical portion 22 with a shoulder 21 bearing on the bottom face 5 of the insulator 17. The extending, preferably conical portion or terminal 22 is disposed axially within the lower part of the sleeve 11 and its end 23 is located a suitable distance away from the lower end of 10 the said sleeve and in a position in which it can not get in contact with the ball, 7, as will be understood from Fig. 1 showing the elevated position of the ball in dotted lines. The stem 20 is formed with a longitudinal groove or passageway 24 through which the chamber enclosing the sparking terminal communicates with the atmosphere.

The upper part 25 of the stem 20 is screw-threaded, and on the said screw-threaded 20 part there is a nut 27 which acts through packing ring 26 on the top face of the insulator 17 for connecting the stem and the insulator.

The gland 30 which keeps the insulator 25 sleeve 11 in position within the body 1 is provided with radial holes 31, and it is covered at its top by a cap 32 preventing the access of dust to the plug and fixed in position by means of a nut 33. Above the nut 30 33 a nut 34 is screwed to the screw threaded part 25 of the stem 20 by means of which the sparking terminal is electrically connected to one terminal of a magneto or the like, the other terminal of said magneto being 35 electrically connected to the cylinder of the engine and the body 1, as is known in the art.

In the operation of the spark plug the compression within the cylinder throws the 40 metallic ball 7 upwards and on the insulator sleeve 11, the chamber enclosing the terminal 22 being connected with a part of lower pressure or the outer air, and as the ball approaches the end 23 of the terminal 45 22 ignition takes place, the electric energy passing from the terminal to the ball. Thereafter, the ball drops on its seat 6, the sparks continuing to be discharged to the ball and from the ball to the flange 5 and to 50 the body 1 near the flange. This is rendered possible because in the meantime air is admitted from without and through the fine groove 24, which air together with the friction of the ball rotating on the spherical 55 flange 5 and the insulator sleeve 11 tends to remove any undesirable, because disturbing deposits such as oil, soot, and other impurities from the ball after each ignition. During the suction stroke the ball is seated 60 on the flange 5 so as to close its axial opening in an air tight manner.

The general construction of the modification shown in Figs. 3 to 5 is substantially the same as that shown in Fig. 1, and the

same reference characters have been used 65 to indicate corresponding parts, so that it is not necessary to repeat the description. In the example shown in Fig. 3 instead of the cylindric insulator 17 and the sleeve 11 a single insulator 11^a is provided which is secured in position by means of a washer 8 and a gland 30, and which is connected with the stem 20 by means of a washer 26^a and a nut 33^a. The stem 20 is provided with an axial bore 24^a. The function of the plug 70 is the same as that of the example shown in Fig. 1.

The example shown in Fig. 4 is similar to that shown in Fig. 3. The lower end of the terminal is formed with a socket 28 having an outwardly flaring lower portion 29. The socket 28 communicates through an axial bore 24^b of the stem 20 with the atmosphere. Above the nut 34^b the stem is provided with radial ducts 36 and the nut 35 has a concave cup shaped upper face 35. For cleaning the plug and for starting the engine I supply a small amount of benzine into the concave cup which flows downwards through the passage 24^b and wets the ball 7. 80 Above the washer 26^b there are two nuts 33^b engaging with the external screw-threads of the stem of the terminal.

Having now described and ascertained the nature of my invention and the manner in 90 which the same is to be performed I now declare what I claim and desire to secure by Letters Patent of the United States is:

1. A spark plug consisting of a tubular conductive body, with a male thread at its lower and a female thread at its upper part, having a spherical flange with a hole as a valve seat at its lower terminal, an insulating sleeve, resting within the wider part of the tubular body, terminating in some distance from aforesaid spherical flange, a washer interposed between the tubular body and the sleeve, a hollow insulating guide within the upper part of aforesaid sleeve, a metallic stem, axially disposed within said guide, terminating with its lowest point shortly above the rim of aforesaid sleeve, a passageway grooved into and extending longitudinally all along the stem, a ball of conductive material movably disposed within the aforesaid spherical flange and the lower rim of the insulating sleeve, means to retain the sleeve within the tubular body, means to cover the insulating members, threaded means engaging the stem to retain it in position and means to electrically connect the stem.

2. In a spark plug comprising a tubular body with a spherical flange at its lower end, a co-axial sleeve of insulating material terminating in some distance from aforesaid flange so as to form a chamber-like space, and a stem of electrically conductive mate-

rial having a groove-like passage-way all along its length and being co-axially arranged within aforesaid members, terminating shortly above the lower terminal of 5 aforesaid sleeve, in combination with a ball of electrically conductive material within aforesaid space.

In testimony whereof I have signed my name in the presence of two subscribing witnesses.

WALTER BRÄGGER.
